UNITED STATES PATENT OFFICE

2,467,703

BALLAST SYSTEM FOR LOCOMOTIVES

Carleton K. Steins, Merion, Pa., assignor to The Pennsylvania Railroad Company, Philadelphia, Pa., a corporation of Pennsylvania

Application March 25, 1946, Serial No. 656,911

3 Claims. (Cl. 105—73)

1

This invention relates to locomotives, and has reference more particularly to steam locomotives of the type disclosed in U. S. Patent No. 2,338,212 granted to me on July 4, 1944. In this patented locomotive the fuel is carried in a compartment at the front end of the locomotive body, and the boiler at the rear end, and the body is supported front and rear respectively beneath the fuel compartment and the boiler by separately powered driving trucks. Thus in such a locomotive as the fuel is used up and the load becomes lighter on the front truck, the wheels of this truck are apt to slip relative to the driving wheels of the rear truck, the load on the latter wheels being substantially constant since the water in the boiler is continually replenished and so kept at a uniform level.

The chief object of my invention is to make it possible to keep the load on the front driving wheels of such a locomotive constant and equal substantially to that on the rear driving wheels. This desideratum is attained as hereinafter more fully disclosed through provision of a simple ballast system comprising a conduit which extends between a ballast compartment in the fuel carrying end of the locomotive and a water storage compartment in a coupled tender, and a pump with valve means and controls whereby ballast water may be transferred in one direction from the tender to the ballast water compartment on a locomotive from time to time as may be required to compensate for the weight loss there due to fuel consumption, and whereby at other times when the locomotive is being re-fueled, the flow may be reversed to return water from the ballast compartment on the locomotive to the tender.

Other objects and attendant advantages will appear from the following detailed description of the attached drawings, wherein—

Fig. 1 is a view in side elevation of a locomotive with a ballast system conveniently embodying my invention.

Figs. 2 and 3 are cross sectional views respectively of the locomotive and its tender taken as indicated respectively by the angled arrows II—II and III—III in Fig. 1.

Fig. 4 is a fragmentary view in side elevation drawn to a larger scale and showing certain details of the pump and control means employed; and,

Fig. 5 is a view corresponding to Fig. 4 showing an alternative embodiment of my invention.

The locomotive herein illustrated has an elongate body 10 with a fuel compartment 11 at the

front end, and with a horizontally arranged boiler 13 at the rear end. Between the fuel compartment 11 and the forward or fire box end 15 of the boiler 13 is a space or cab 16 for the engine crew. The body 10 is supported at opposite ends by trucks 17 and 18 which underly the fuel compartment 11 and the boiler 13, and which, it is to be understood, are pivoted for independent swivelling movement to the body. It is moreover to be understood that the trucks 17 and 18 are separately powered after the manner disclosed in Patent No. 2,338,212 previously referred to herein and have associated with them smaller individual leading guide trucks 19 and 20. Coupled with the locomotive at the rear end is a tender 21 with a storage compartment 22 for water.

In carrying out my invention I provide the locomotive at the front end of its body with ballast water compartments 24, one at each side of the fuel compartment 11. To these water compartments 24 are connected branches of a conduit 25 which extends rearwardly to the tender 21 as shown in Fig. 1, where it is connected to the water compartment in the latter. Interposed in the conduit 25, as best shown in Fig. 4, are two by-passes 27 and 28, a unidirectional rotary pump 29 and a number of hand valves 30, 31, 32 and 33. The pump is arranged to be driven by a turbine indicated at 35 which is supplied with steam from the boiler 13 through a pipe 36 under control of a hand valve 37. The parts just described are all preferably located in the cab so as to be conveniently accessible to the engine crew.

Operation

With the construction shown in Figs. 1—4, compensation can be made from time to time by the engine crew for the decrease in weight on the driving wheels of the forward powered truck 17 due to fuel consumption, so that a substantially uniform load may be maintained on said drivers commensurate with the fixed load on the drivers of the powered rear truck to prevent wheel slippage. This is accomplished by closing the valves 30 and 33 and opening the valves 31 and 32 and then starting the pump 29. Under these conditions, water will be drawn from the tender 21 and delivered to the ballast tanks 24 on the locomotive, the flow being then as indicated by the full line arrows in Fig. 4. Upon transfer of the necessary amount of the water (which may be determined by a depth gauge, not illustrated) to the ballast compartments 24, the pump 29 is stopped and the valves 31 and 32 closed until

another compensating operation is required, which is effected by repetition of the above procedure. When the fuel storage compartment 11 on the locomotive is being subsequently recharged, the ballast water may be returned to the tender from the ballast water compartments 24 by keeping the valves 31 and 32 closed, opening the valves 30 and 33, and then starting the pump 29; when the flow will be as indicated by the dotted arrows in Fig. 4, i. e. clockwise through the by-pass 28, then through the pump 29, and then counter-clockwise through the by-pass 27.

In the alternative embodiment of my invention shown in Fig. 5, separate rotary pumps 29a and 39 respectively are interposed in the by-passes 27a and 28a together with hand valves 31a and 32a, the pump turbines 35a and 40 being oppositely rotative and respectively supplied with steam from the boiler through pipes 36a and 41, under control of hand valves 31a and 41a. Also interposed in the by-pass pipes 27a and 28a are check valves 42 and 43 respectively. When water is to be transferred from the tender to the ballast water compartments 24 on the locomotive with this alternative arrangement, the valve 31a is opened, the valve 32a closed and the pump 29a alone used, when the flow will be as indicated by the solid arrows in Fig. 5 through the by-pass 27a, with the check valve 43 acting to prevent flow through the by-pass 28a. On the other hand, for transfer of water from the ballast compartments on the locomotive to the tender the valve 32a is opened, the valve 31a closed, and the pump 39 employed alone, when the flow will be as indicated by the dotted arrows in Fig. 5 through the by-pass 28a, with a check valve 42 preventing flow through the by-pass 27a.

Having thus described my invention, I claim:

1. A ballast system for a steam locomotive having a body with a fuel compartment at one end and a boiler at the other end, separately powered drive wheel trucks supporting the body at opposite ends respectively beneath the fuel compartment and the boiler, and a coupled tender with a water storage compartment; said system including a water ballast compartment on the locomotive in the region of the fuel compartment, a single conduit extending between the tender and said ballast water compartment, a normally quiescent uni-directional pump interposed in the conduit, means for driving the pump, by-pass piping incorporated in the conduit around the pump, and valve means for controlling the by-pass piping to determine directional flow of the water through the conduit under propulsion of the pump either from the tender to the ballast water compartment on the locomotive to compensate for weight decrease on the drivers under the fuel compartment as the fuel is consumed, or from the ballast water compartment on the locomotive to the tender to compensate for weight increase on the drivers under the fuel compartment during re-fueling.

2. A ballast system for a steam locomotive having a body with a fuel compartment at one end and a boiler at the other end, separately powered drive wheel trucks supporting the body at opposite ends respectively beneath the fuel compartment and the boiler, and a coupled tender with a water storage compartment; said system including a water ballast compartment on the locomotive in the region of the fuel compartment, a single conduit extending between the tender and said ballast water compartment, a normally quiescent uni-directional pump interposed in the conduit, means for driving the pump, a by-pass pipe shunting the pump, another by-pass pipe extending between the inlet of the pump and that end portion of the conduit which leads from the ballast water compartment of the boiler, and valves respectively in the by-passes adapted to be closed to permit pumping of water from the tender to the locomotive to compensate for decrease in weight on the truck under the fuel compartment due to fuel consumption, and valves respectively in the conduit at the inlet and outlet sides of the pump adapted to be closed to permit pumping of water from the ballast water compartment on the locomotive to the tender during recharging of the fuel compartment.

3. A ballast system for a steam locomotive having a body with a fuel compartment at one end and a boiler at the other end, separately powered drive wheel trucks supporting the body at opposite ends respectively beneath the fuel compartment and the boiler, and a coupled tender with a water storage compartment; said system including a water ballast compartment on the locomotive in the region of the fuel compartment, a single conduit extending between the tender and said ballast water compartment, a normally quiescent pump interposed in the conduit and adapted to induce flow from the tender to the ballast water tank on the locomotive to compensate for decrease of the weight on the truck beneath the fuel compartment as the fuel is being consumed, a by-pass pipe around the pump, a normally quiescent reversely operative pump in the by-pass adapted to induce flow from the ballast water tank on the locomotive to the tender, and a hand valve in the by-pass adapted to be closed when the first mentioned pump is used, and a hand valve in the conduit adapted to be closed when the second pump is used.
